UNITED STATES PATENT OFFICE.

THOMAS R. BROWN, OF SPARKILL, NEW YORK, ASSIGNOR TO THE WESTINGHOUSE AIR BRAKE COMPANY, OF WILMERDING, PENNSYLVANIA, A CORPORATION OF PENNSYLVANIA.

ELECTRIC COUPLING FOR TRAIN-LINE CIRCUITS.

1,242,517.

Specification of Letters Patent.

Patented Oct. 9, 1917.

Application filed July 14, 1914. Serial No. 850,990.

To all whom it may concern:

Be it known that I, THOMAS R. BROWN, a citizen of the United States, and a resident of Sparkill, in the county of Rockland and State of New York, have invented a certain new and useful Improvement in Electric Couplings for Train-Line Circuits, of which improvement the following is a specification.

10 This invention relates to mechanism for coupling electric circuits between the cars or other vehicles of a train, and more particularly to that type of electric coupling in which each counterpart head is provided 15 with a movable contact carrier and a plurality of fixed contacts or fingers connected to the respective train line circuits, one of said carriers being adapted to be projected from one coupler head to the other, and 20 electrically connect the corresponding contact fingers of the two couplers.

One of the objects of my present invention is to provide improved fluid pressure means for projecting the movable contact carrier, 25 and for locking the same in its coupled position. Another object is to provide improved means for releasing the carriers; and another object is to provide an improved combined car and electric coupler.

30 In the accompanying drawings: Figure 1 is a vertical longitudinal section, taken substantially on the line 1—1 of Fig. 2; Fig. 2, a central horizontal section, showing one form of my improved electric coupling contained within the car coupler; Fig. 3, a fragmentary vertical section taken on the line 3—3 of Fig. 2; Fig. 4, a detail view of the rotatable locking stem; Fig. 5, a vertical longitudinal section showing two counterpart 35 couplers coupled together; Fig. 6, a plan of same; Fig. 7, a front end or face view of one of the couplers; Fig. 8, a vertical longitudinal section of a modified electric coupling adapted to be attached to or suspended from the coupler or draw bar; Fig. 9, a plan of same; Fig. 10, a vertical longitudinal section taken substantially on the line 10—10 of Fig. 9; Fig. 11, a fragmentary transverse section showing the locking device; and Fig. 50 12, a detail view of the rotatable locking stem of the modification shown in Fig. 8.

According to the construction shown in Figs. 1 to 7, my improved electric coupling

is illustrated in connection with a car coupler, 12, of the rigid lock type, and having 55 interlocking hook shaped projections, 14, provided with vertical plane surfaces inclined at an angle to the line of draft, and adapted to engage and interlock with each other by a relative lateral movement of the 60 coupler heads as the same are brought together in coupling, there being also a pivoted lock (not shown) for holding the parts in coupled position. Centrally located within the casting of the coupler is a chamber 65 containing the electric contacts and devices for connecting up electric circuits through the train. These devices comprise a plurality of contact fingers, 15, connected to the respective train line circuits, a movable contact carrier, 16, having a series of contact bars, 17, and fluid pressure mechanism for projecting said carrier into the corresponding chamber of the counterpart coupler to establish electrical connection between the 75 contacts of the respective circuits. These carriers are in the form of slides, and normally occupy a position with the outer ends substantially in the plane of the meeting faces of the couplers, as shown in Fig. 1. 80 For the purpose of projecting the slides, one or more cylinders and pistons may be employed, but according to one of the features of my improvement, I provide a plurality of pairs of telescoping cylindrical 85 sections, one portion, 20, being formed with the carrier, and the other part, 21, acting against the casting of the coupler. Each pair of telescoping sections contains a helical spring, 22, which is confined between the 90 head of section, 21, and the loosely fitting head, 24, by means of connecting links, 23, the head, 24, being normally at the closed end of the cylinder, 20, when the parts are in uncoupled position, as indicated in Fig. 95 2. By means of this construction, the cylinders may be of small diameter, about equal to the vertical thickness of the carrier, and may be arranged in a horizontal row occupying a space about equal to the width of 100 the carrier, thus forming a very compact structure, and so economizing the space as to be located entirely within the chamber formed in the central portion of the coupler casting.

105 In order to lock the carrier in its pro-

- jected position, a projecting stem, 25, is mounted in the coupler casing and fits within the cylinder, 26, of the carrier, thereby serving also as a guide for the carrier.
- 5 The guide, 25, and cylinder, 26, have a groove and pin connection, 27 and 28, and the guide is mounted to have a partial rotary movement when the pin, 28, reaches the end of the longitudinal groove, 27, where 10 there is a short right angled extension to permit a turning movement of the stem, and thereby lock the slide or carrier against a return movement. A small piston, 30, having a stem, 29, provided with a notch engaging a projection, 31, on the guide stem, 25, is employed for releasing the lock, the piston being located in the cylindrical chamber, 32, and operated in one direction by a spring, 33, and in the opposite direction by fluid pressure, or at certain times by a stem, 34, which may be depressed by hand when the fluid pressure is not available. The guide, 25, is preferably made tubular with a passage through the same for 15 admitting fluid into the cylinder, 26, and from thence through suitable ports into the several cylindrical sections, 20. In this case, the cylinder, 26, also acts as an additional cylinder to assist in projecting the carrier.
- 20 Suitable passages, 35 and 36, are provided for the escape of leakage and for supplying fluid under pressure to the unlocking pistons of both couplings through the connecting nipples, 37, when the operating cock on 25 either one of the couplings is manipulated for releasing the locking device, in a similar manner to that set forth in my prior application Serial No. 823,970, filed March 11, 1914.
- 30 Any suitable form of cock and pipe connections may be employed for supplying fluid to the cylinders for projecting the carrier and for releasing the locking device, but according to another feature of my im- 35 provement, I provide a valve means by which both functions may be performed with a single cock, and a single pipe connection to the coupling. This valve device comprises a piston valve, 40, normally seated 40 in one position by spring, 41, to close communication to ports, 38 and 36, and the un- 45 locking cylinder, and having a small by-pass port, 42, for supplying fluid to the projecting cylinders, 20. The supply of fluid to 50 said piston is controlled by the cock, 43, having a small port, 44, and a large port, 45, with the single pipe connection, 46. The piston, 40, also controls an exhaust port, 47, to the atmosphere. The piston valve, 55 40, may preferably be mounted within an enlarged cylindrical head, 39, of the rotatable guide stem, 25.

When the couplers are brought together in coupled position, as indicated in Fig. 6, 60 and it is desired to connect the train line cir-

cuits, the cock, 43, on one of the couplers is turned from its closed position to the position indicated in Fig. 2, with the small port, 44, open. Fluid is thereby supplied slowly through pipe, 46, to the piston, 40, and 70 through the by-pass port, 42, to the cylinders, 26 and 20. Under these conditions, the fluid flows through ports, 44 and 42, gradually without accumulating a sufficient pressure on the piston, 40, to cause a move- 75 ment of the same against the spring, 41. The exhaust port, 47, and port, 48, thus remain closed, and the pressure accumulating in cylinders, 26 and 20, forces the contact carrier, 16, outward against the corresponding carrier in the counterpart coupling, thus compressing the springs, 22, in the cylinders, 20, of said counterpart coupler, and moving both carriers to the coupled position, as indicated in Fig. 5, in 80 which the contact bars, 17, establish electrical connection between the respective contact fingers, 15, of the circuits through the train. During this movement, the cylinder, 26, slides upon the guide stem, 25, the pin, 90 28, moving to the end of the groove, 27, whereupon the spring, 33, acting on piston, 30, and stem, 29, move the same to partially rotate the guide, 25. The pin, 28, is thus thrown into the offset extension of the 95 groove, and locks the cylinder, 26, and the contact carrier against a return movement. The cock, 43, may then be turned back to its normal closed position, and the parts will remain in the coupled position as long as 100 desired, even though the compressed air escapes by leakage from the cylinders, and the pressure is reduced to that of the atmosphere.

When it is desired to uncouple, the contact carrier must first be withdrawn, and for this purpose either one of the cocks, 43, of the counterpart couplers may be turned to the position for opening the large port, 45. Fluid is then supplied to the piston, 40, 105 much more rapidly than it can pass through the restricted by-pass port, 42, consequently accumulating on the piston to move the same against the spring, 41, to its opposite position, thus 110 closing the port, 42, and opening port, 38, and the exhaust port, 47. Fluid then flows through ports, 38, and 36, to the cylinders, 32, of both the interlocking pistons, 30, and either one which happens to be in the 115 upper or locking position is forced downward, thereby turning the guide, 25, so that the locking pin, 28, occupies the longitudinal portion of the groove, 27, and the springs, 22, then act to return the contact carriers to the uncoupled or release position. The couplers may then be separated in the usual manner.

In order to hold the counterpart coupler heads firmly locked together, and prevent 130

any relative lateral tilting movement, a spring actuated bolt, 18, may be provided at one side of the coupler, and adapted to engage a clamping surface, 19, on the other side of the counterpart coupler when the same are brought together.

For coupling up the train pipe lines, each coupler may be provided with passages having gasket openings, 50, and hand operated coupling members, 51.

Instead of mounting my improved electric coupling mechanism in the chamber formed within the car coupler casting, it will be apparent that the same may be contained in a separate casing, 12^a, adapted to be attached to the coupler, or draw bar, as shown in Figs. 8 to 12 of the drawings, and in which the corresponding parts are marked with the same reference characters as in the other figures. The relative position of some of the parts, as shown in this modification, is slightly changed, but the operation is the same as that heretofore described, as will be readily understood.

Having now described my invention what I claim as new and desire to secure by Letters Patent is:

1. In an electric train line coupling, the combination with a casing containing a plurality of fixed contacts connected to train line circuits, and a movable contact carrier having corresponding contacts, of a plurality of cylinders for projecting said carrier to electrically connect fixed contacts of counterpart couplings, said cylinders being rigidly connected to said carrier, and means for controlling the admission of fluid to said cylinders.

2. In an electric train line coupling, the combination with a casing containing a plurality of fixed contacts connected to train line circuits, and a movable contact carrier having corresponding contacts, of a plurality of cylinders for projecting said carrier to electrically connect fixed contacts of counterpart couplings, said cylinders being horizontally arranged and of a diameter substantially the same as the thickness of said carrier.

3. In an electric train line coupling, the combination with a casing containing a plurality of fixed contacts connected to train line circuits, and a movable contact carrier having corresponding contacts, of a plurality of cylinders for projecting said carrier to electrically connect fixed contacts of counterpart couplings, said cylinders being formed in telescoping sections supported on said carrier, and means for admitting fluid thereto.

4. In an electric train line coupling, the combination with a casing containing a plurality of fixed contacts connected to train line circuits, and a movable contact carrier having corresponding contacts, of a fluid

pressure cylinder formed in telescoping sections for projecting said carrier and supported thereon, and a spring within said cylinder for opposing the inward movement of said carrier.

5. In an electric train line coupling, the combination with a casing containing a plurality of fixed contacts connected to train line circuits, and a movable contact carrier having corresponding contacts, of a plurality of cylinders for projecting said carrier to electrically connect fixed contacts of counterpart couplings, said cylinders being formed in telescoping sections supported on said carrier, springs for opposing the inward movement of said carrier, and means for admitting fluid to said cylinders.

6. In an electric train line coupling, the combination with a casing containing a plurality of fixed contacts connected to train line circuits, and a movable contact carrier having corresponding contacts, of fluid pressure means for projecting said carrier, a rotatable guide for said carrier, and locking means connected with said guide for holding the carrier in its projected position.

7. In an electric train line coupling, the combination with a casing containing a plurality of fixed contacts connected to train line circuits, and a movable contact carrier having corresponding contacts, of fluid pressure means for projecting said carrier, a guide and cylinder having a pin and groove connection, and means for partially rotating one of said parts to lock said carrier in its projected position.

8. In an electric train line coupling, the combination with a casing containing a plurality of fixed contacts connected to train line circuits, and a movable contact carrier having corresponding contacts, of fluid pressure means for projecting said carrier, a guide and cylinder having a pin and groove connection, and a piston for partially rotating said guide.

9. In an electric train line coupling, the combination with a casing containing a plurality of fixed contacts connected to train line circuits, and a movable contact carrier having corresponding contacts, a cylinder, a tubular guide stem fitting therein, and means for admitting fluid through said guide into the cylinder for projecting said carrier.

10. In an electric train line coupling, the combination with a casing containing a plurality of fixed contacts connected to train line circuits, and a movable contact carrier having corresponding contacts, of a plurality of cylinders for projecting said carrier, a tubular guide fitting one of the cylinders, and means for admitting fluid through said guide to said cylinders.

11. In an electric train line coupling, the combination with a casing containing a plurality of fixed contacts connected to train

- line circuits, and a movable contact carrier having corresponding contacts, of a fluid pressure cylinder for projecting said carrier, a locking device for said carrier, a piston for releasing the lock, a single pipe connection, and manually controlled valve means for operating the projecting cylinder and the releasing piston.
12. In an electric train line coupling, the combination with a casing containing a plurality of fixed contacts connected to train line circuits, and a movable contact carrier having corresponding contacts, of a fluid pressure cylinder for projecting said carrier, a locking device for said carrier, a piston for releasing the lock, a piston valve controlling communication to said releasing piston and having a restricted by-pass port communicating with the projecting cylinder, and a cock having ports of different capacities for admitting fluid to said piston valve.
13. In an electric train line coupling, the combination with a car coupler having a casing formed with a chamber, of a plurality of fixed contacts mounted within said chamber and connected to the respective train line circuits, a contact carrier having corresponding contacts, and a fluid pressure cylinder also mounted in said chamber for projecting said contact carrier to electrically connect the fixed contacts of counterpart couplings.
14. In an electric train line coupling, the combination with a car coupler having a casing formed with a chamber, of a plurality of fixed contacts mounted within said chamber and connected to the respective train line circuits, a contact carrier having corresponding contacts, and a plurality of fluid pressure cylinders arranged horizontally within said chamber for projecting said carrier.
15. In an electric train line coupling, the combination with a car coupler having a casing formed with a chamber, of a plurality of fixed contacts mounted within said chamber and connected to the respective train line circuits, a contact carrier having corresponding contacts, a fluid pressure cylinder for projecting said contact carrier, a spring actuated clamping bolt at one side of said casing, and a clamping surface at the other side for engaging the corresponding clamping means of a counterpart coupler.
